UNITED STATES PATENT OFFICE.

WILLIAM ALEXANDER McRAE, OF BRECHIN, ONTARIO, CANADA.

LIQUID-LEVEL INDICATOR.

Application filed December 1, 1924. Serial No. 753,065.

This invention relates to improvements in liquid level indicators as described in the present specification and illustrated in the accompanying drawings which form part of the same.

The invention consists essentially of the novel features pointed out broadly and specifically in the claims for novelty following a description containing an explanation in detail of an acceptable form of the invention.

The objects of the invention are to give more comfort to the driver of a motor car and to overcome the necessity of removing the cushion and lifting the seat in certain types of cars; and generally to insure economical and effective results.

In the drawings, Figure 1 is a perspective view of the seat broken away to disclose the tank and the tank filler and contiguous parts.

Figure 2 is an enlarged perspective view of the invention looking at the under side.

Figure 3 is a side view of the preferred form of the invention.

Figure 4 is a view of the spring-held cover for the tubes.

Figure 5 is a plan view of the cover showing the tubes in dotted lines.

Like numerals of reference indicate various parts in the different figures.

Referring to the drawings, the tank filler 1 has the cap 2 pivoted at 3 by the bolt 4, which continues on downwardly between the bands 5 which are held in position around the tubes 6 and 7 by the screws 8 and 9 and the bolt 4 at the other end is encircled by the spring 10 and the nut 11 forms the adjustment for same. Spring 10 holds the cover 2 in place over the open ends of the tubes 6 and 7 thus avoiding any dust entering or any rattle from same while the car is in motion. The tubes continue on downwardly at 12 and 13 and are bent inwardly at 14 and 15 having the union joints 16 and 17 midway of their length, the straight parts 18 and 19 are rigidly secured to the spout 20 which is reduced at 21 to suit the curve of the tank 22 and this reduced portion 21 is open at 23 and has the flanged part 24

projecting therefrom to form an abutment for the arm 25 which is secured by the bolt 26 passing through the opening 23 and is rigidly secured to the top of the spout 20 by the nut 27.

The arm 25 carries the U-shaped bearing bracket 28 which is pierced midway of its length on the two legs of the U to receive the bolt 26 and on one leg of the U the bridge piece 39 having the legs 40 and 41 to span the opening 42 is rigidly secured. The closed end of the U is turned up and pierced at 43, 44, 45 and 46 to form the sliding member for the loop 47 which has the rigid piece 48 at the centre to operate with the forked end 49 of the indicator arm 50 which registers on the dial 51 as the float rises and falls. The loop 47 forms the sliding member and is operated by the arm 53 which is pivoted at 54 and at the other end 55 is pivoted to the short leg 56 of the U-shaped arm 57. The closed end of the U-shaped arm 57 is pivoted at 58 through the hole 59 of the arm 25 and the long leg of the U-shaped arm carries the float 60 at the extreme end.

In the operation of the invention, the float mechanism, which includes the arm portion, is first placed inside the tank and then securely fastened to the receptacle, so that when the tank is being filled the float will rise therein and indicate the quantity of gasoline that is inside through the indicator attached in a suitable place. This device is for certain well-known types of cars which have their tanks located underneath the driver's seat and thus eliminates the necessity of the passengers moving from their seats and at the same time indicate the quantity of gasoline in reserve.

The device may, of course, be changed to meet with the requirements of the different tank constructions without in any way departing from the main features as herein shown and described.

What I claim is:

A liquid level indicator comprising an arm having guide brackets on one face thereof, a bracket adapted for fastening said arm to a receptacle, a rod pivotally mounted in one end of said arm and having a crank

end adjacent to said arm, a float secured to the outermost end of said rod, a loop slidably mounted in said guide brackets and a link connecting one end of said loop to the crank end of said rod, said loop having a cross member intermediate its ends, a spindle pivotally mounted at one end at a point adjacent to said loop and having a fork-shaped portion at right angles there-

to engaging said cross member of said loop, 10 an indicator secured at the other end of said spindle, and a dial secured adjacent to said indicator.

In testimony whereof I have affixed my signature this 28th day of November, 1924 15
at the city of Toronto.

WILLIAM ALEXANDER McRAE.
